DESCRIPTION

FIG. 1 is a perspective view of a container showing an embodiment of our new design and taken from above the container;

FIG. 2 is a top plan view of the container shown in FIG. 1;

FIG. 3 is an elevation view of the container shown in FIG. 1 taken from a direction perpendicular to one of the sides;

FIG. 4 is a perspective view of the container of FIG. 1 taken from below the container;

FIG. 5 is a bottom plan view of the container of FIG. 1; and,

FIG. 6 is an elevation view of the container shown in FIG. 1 taken from a direction along the angle bisector of the angle joining any two sides.
